UNITED STATES PATENT OFFICE.

SUSAN EMILY FRANCIS, OF WELLINGTON, NEW ZEALAND.

CYCLING-SKIRT.

SPECIFICATION forming part of Letters Patent No. 614,097, dated November 15, 1898.

Application filed January 22, 1898. Serial No. 667,598. (No model.)

To all whom it may concern:

Be it known that I, SUSAN EMILY FRANCIS, a subject of the Queen of Great Britain, residing at 54 Lambton Quay, Wellington, in 5 the Colony of New Zealand, have invented an Improved Cycling-Skirt, of which the following is a specification.

This invention relates to skirts worn by ladies when riding upon bicycles and similar 10 vehicles; and the object of the invention is to provide a skirt which may have an ordinary appearance when the wearer is walking and when required for riding may be easily and rapidly adjusted to provide room for the 15 vertical movement of the legs without dragging the knees or unduly exposing the legs of the rider.

It is well known to lady cyclists that the ordinary skirt is uncomfortable when used for 20 riding and by the movement of the legs is unavoidably raised to an undesirable degree.

According to this invention the shape of the skirt closely follows existing forms; but I provide two gussets in front to give fullness 25 where required for the movement of the knees. The gussets are formed in any ordinary manner, as by inserting a piece of material shaped as required.

When the skirt is used for walking, the 30 gussets, which would otherwise be unsightly, are hidden by buttoning or otherwise fastening the edges of the gussets together, when the skirt has the appearance of an ordinarily-cut skirt. These said edges may be so finished and trimmed and the buttons so arranged as to be ornamental and conform in 35 a great measure to fashions in vogue.

In order that my invention may be most easily understood, reference will be made to 40 the accompanying drawings while giving a detailed description.

Figure 1 is a front view of the skirt as worn when the wearer is walking. Fig. 2 is a similar view of the same as worn when the wearer 45 is riding a cycle. Fig. 3 is a front view showing the skirt unfastened for adjusting upon the wearer. Fig. 4 is a back view of the skirt, showing the ordinary saddle-gore. Fig. 5 is a representation of the pattern of the half- 50 back. Fig. 6 is a representation of the pattern of the side piece. Fig. 7 the pattern

of the half-front, and Fig. 8 the pattern of a band.

Similar letters of reference indicate corresponding parts throughout the views.

In making a skirt according to my invention the material is cut out to the shape of the patterns shown in Figs. 5 to 8, inclusive. The half-back *a* of Fig. 5 is then united by its edge *a'* *a*² to the side piece *b* of Fig. 6 60 along its edge *b'* *b*², and the said side piece *b* is united by its edge *b*³ *b*⁴ to the half-front *c* of Fig. 7 along its edge *c'* *c*², and the band *d* of Fig. 8 is united by its edge *d'* *d*² to the half-front *c* in the position shown by dotted 65 lines in Fig. 7.

It will be readily understood by a skilled dressmaker that the material is cut out in duplicate and that darts, such as shown by dotted lines at *b*⁵ in Fig. 6, must be introduced to shape the skirt to the figure of the wearer and that the skirt may be lined and trimmed in any desired manner.

The buttons *f* of Figs. 1, 2, and 3 are sewed to the side pieces *b*, and when the skirt is 75 used for walking the bands *d* are buttoned, as shown in Fig. 1, but when used for riding the said bands are unbuttoned and allowed to go free. In this manner fullnesses are formed or the width of the skirt is extended 80 so that accommodation is provided for the knees of the rider to move freely.

Fig. 3 shows the top portion of the front piece and bands let down to adjust the skirt upon the wearer. When in position, the skirt 85 is fastened by uniting the hooks *c*³, Fig. 3, to the eyes *c*⁴ upon the waistband *g*.

Fig. 4 shows the usual saddle-gore *h* at the back of the skirt. By this provision the skirt is made to fall gracefully from each side of 90 the saddle.

Buttonholes *f'*, Fig. 2, may be provided to engage a button suspended from the knee of the knickerbockers of the wearer by a short elastic band to keep the skirt in place in a 95 side wind.

The buttons *f* and hooks and eyes *c*³ and *c*⁴ may be replaced by any ordinary form of fastener; but I have shown such fasteners as have proved to be most useful in practice, 100 and I wish it to be understood that I am aware a skilled person may modify the de-

tails of the invention without departing from the spirit of the same.

What I claim, and desire to secure by Letters Patent of the United States, is—

- 5 1. In combination with a skirt, a piece *c* inserted permanently therein, a band secured by one of its edges thereto and having its other edge detachably connected with the skirt to decrease or increase the width there-
10 of, substantially as described.
2. In combination with a skirt, a piece *c* inserted permanently therein bands *d* secured by one edge to each edge of said piece with their other edges detachably secured to the
15 skirt, the upper part of said piece being detachable from the skirt to fold downwardly, substantially as described.
3. A skirt comprising the side pieces *b*, *b*, having the edges *b*³ *b*⁴, the front pieces hav-

ing the edges *c*', *c*² connected with the side 20 pieces, and the bands *d* permanently secured to the front and detachably connected with the side pieces, substantially as described.

4. In combination with a skirt, a band attached thereto permanently at one edge and 25 extending from the top downwardly, and detachable fastenings between the skirt and the free edge of the band, the distance between the detachable and permanent fastening means being greater than the width of 30 the band, substantially as described.

In witness whereof I have hereunto subscribed my name this 23d day of November, 1897.

SUSAN EMILY FRANCIS.
